NICHOLAS STUKALO-COYLO, OF HARTFORD, CONNECTICUT.

SAFETY DEVICE FOR PUNCHES.

1,118,698.

Specification of Letters Patent. Patented Nov. 24, 1914.

Application filed June 3, 1914. Serial No. 842,617.

To all whom it may concern:

Be it known that I, NICHOLAS STUKALO-COYLO, a subject of the Czar of Russia, and a resident of Hartford, in the county of 5 Hartford and State of Connecticut, have invented a new and Improved Safety Device for Punches, of which the following is a full, clear, and exact description.

This invention relates to power machinery 10 and has particular reference to safety appliances therefor, the primary purpose being to provide an attachment for a machine punch or the like having a reciprocating part whereby it is practically impossible for 15 the operator to have his hands injured by a movement or impact of the reciprocating part of the machine.

The foregoing and other objects of the invention will hereinafter be more fully described and claimed and illustrated in the drawings forming a part of this specification in which like characters of reference indicate corresponding parts in all the views, and in which—

25 Figure 1 is a front elevation of a machine having my improvement attached thereto; Fig. 2 is a partial side elevation of the same, the punch slide being elevated; and Fig. 3 is a view similar to Fig. 2 but 30 indicating the slide at or near the lower limit of movement.

While the drawings indicate a preferred embodiment of the invention, the same including an upright reciprocating punch, it 35 is to be understood that the invention with slight modifications is adapted for use upon various types of machines including not only vertical power punching presses and cutters, but also straight side power presses, 40 inclinable power presses, drawing presses, spinning lathes, and foot and screw presses. This improvement obviously may be made of various materials in different sizes and shapes adapting it for use in any of the 45 foregoing or other machines, and being of a simple nature, may be manufactured at a low cost. It is to be observed, also, that the operation of the machine does not interfere with the rapid and easy manipulation by 50 the operator of his work, and its functions are independent of the foot or other controlling means under the direct operation of the operator. Many accidents in 55 machines of the character indicated are due to the accidental or premature drop or movement of the punch or other reciprocating

member, but in this device the guard member being carried by the reciprocating member is always certain of action irrespective of the cause for the movement of the reciprocating part. 60

Referring more particularly to the drawings, I show at 10 a conventional form of vertical press having a reciprocating slide 11 carrying what may be regarded as a die 65 12. At the base 13 of the machine is secured a fixed die block 14 with which the die 12 co-operates.

At 15 is shown a lever or arm pivoted at its upper end to a bracket 16 secured to the slide 11 whereby the arm is moved positively with the reciprocations of the slide. The pivot 17 of the arm extends parallel to the front of the machine and hence the movements of the arm around such pivot are 70 in a plane substantially perpendicular to the front of the machine, or such as to cause the lower end of the arm to vibrate toward and from the operator standing in front of the machine. To said lower end of the arm 75 is adjustably or rigidly connected a blade 18, the connection being made through slots 19 formed in one of the parts and screws 20 carried by the other of said parts and projecting through the slots. The blade is of 80 substantially right angular form, being provided with an active face 18' extending horizontally or at right angles to the direction of movement of the slide. Said face 18' may 85 be coated with rubber or some other frictional material to increase its efficiency, if desired. 90

At any suitable place there is secured to a fixed part of the frame of the press a bracket 21 secured by screws or bolts 22 extending through slots 21' in the bracket. 23 indicates an axle, the form and position of which will depend upon the type of machine and the place of location of the bracket, said axle being secured rigidly in the bracket by means 95 of a set screw 24 or the like. Said axle is projected laterally through a cam slot 15' in the arm 15. The arm 15 is bent adjacent the slot to provide for vertical and inclined portions of said slot. The vertical portion of 100 the slot will be understood to be the one parallel to the line of movement of the slide, and the other portion of the slot is so disposed with respect to that first mentioned as 105 to cause the arm to swing outwardly while it is being carried downwardly with the slide, the axle 23 being held in fixed position 110

after being once adjusted. The axle may be provided with collars 25 and 26 on opposite sides of the arm to insure proper operation of the arm.

6 The operation of the machine may be briefly described as follows: With the parts arranged as shown in Figs. 1 and 2, the operator, standing and working in front of the machine on the opposite side of the slide 10 from the blade 18, will place the work between the die and the die block, and when the slide and die move downwardly the blade 18 will first move directly downwardly due to the vertical portion of the slot 15' and will 15 then subsequently swing outwardly due to the inclined portion of the slot and thereby sweeping the operator's hands or fingers out of the way of the die but without disturbing the work or interfering in any manner with 20 the proper operation of the machine. When the slide and die make their return movement, the pivot 17 will obviously cause the movement of the arm and blade in the reverse direction.

25 Having thus described my invention, I claim as new and desire to secure by Letters Patent:

1. The combination with a power press including a frame, a slide movable in said 30 frame, a die carried by the slide, and a die block held in fixed position and coöperating with said die, of an arm pivotally connected to and movable by one side of said slide and

having a cam slot therethrough, a blade adjustably secured to the free end of the arm 35 and extending thence laterally to guard the space between the die and die block at the front of the machine, and an axle secured in rigid position upon the frame and extending through said slot to determine the movement of the arm around its pivot.

2. In a machine of the class set forth, the combination with a frame, a slide reciprocating therein, a die carried by the slide, and a die block coöperating with the die, of an arm 45 pivoted at one end to the slide, the axis of the pivot being parallel to the front of the machine, said arm being provided at its free end with a blade extending parallel to the front of the machine and guarding the space 50 between the die and die block, a block rigidly secured to one side of the frame and adjustable up and down along the same, and an axle carried by said block and coöperating with the arm to cause the arm and blade 55 to move downwardly and forwardly simultaneously with the downward movement of the slot.

In testimony whereof I have signed my name to this specification in the presence of 60 two subscribing witnesses.

NICHOLAS STUKALO-COYLO.
